INVENTOR
GEORGE W. DOVER

BY *Perley H. Plant*
ATTORNEY

UNITED STATES PATENT OFFICE.

GEORGE W. DOVER, OF PROVIDENCE, RHODE ISLAND.

CURTAIN HOLDER.

Application filed May 15, 1925. Serial No. 30,401.

This invention relates to an improved holder for curtains which is adapted to support a plurality of curtains and curtain draperies in such a manner as to permit the same being turned into the usual position in front of a window or turned into position away from in front of the window when it is desired to open the window, the structure also permits the ready removal of the curtain and the curtain supporting structure from the window when desired.

Certain objects of the invention relate to the provision of a structure of the character described which is adapted to permit the curtains and draperies to be readily turned into position in front of the window or into position away from the front of the window, and so constructed as to releasably hold the curtains in either of the above positions until moved into another position, as well as to permit the holder and curtains carried thereby to be bodily removed from the window or replaced thereon when desired.

A further object of the invention is to provide a structure of this character wherein the curtains and draperies may be placed in position on the window below the valance and raised and held in such position that the upper portions of the curtains and draperies will be behind and covered by the valance, while the curtains and draperies may be lowered below the valance before being turned away from in front of the window.

A further object of the invention relates to the provision of an improved bracket structure for supporting the holder as well as the provision of means whereby the curtain holder structure may be placed on the bracket or bodily removed therefrom without removing the bracket from the frame.

Another object of the invention relates to the provision of the curtain supporting members so formed as to support the curtains and draperies in off-set position relative to each other as well as the provision of extensible curtain supporting members whereby they may be readily adapted for use in connection with windows of different widths.

Other objects and advantages of the invention relate to certain improved details of construction and methods of operation as

will be more fully set forth in the detailed description to follow:

Referring to the drawings:

Fig. 1 is a front elevational view of a portion of a window frame illustrating the position of the valance rod and that part of the curtain holder mechanism located upon one side of the window.

Fig. 2 is a top plan view of the structure shown in Fig. 1.

Fig. 3 is a side elevational view of the structure shown in Fig. 1.

Fig. 4 is an enlarged top plan view of a portion of one of the curtain supporting members taken along the line 4—4 of Fig. 1.

Fig. 5 is a sectional view taken along the line 5—5 of Fig. 4.

Fig. 6 is a side view of a portion of one of the curtain supporting members.

Fig. 7 is a sectional view taken along the line 7—7 of Fig. 6.

Fig. 8 is an enlarged top plan view of the upper bracket, supporting the holder.

Fig. 9 is an enlarged sectional view taken along the line 9—9 of Fig. 3.

Fig. 10 is an enlarged sectional view taken along the line 10—10 of Fig. 3 showing a portion of the rotating shaft and the curtain retaining hook.

Fig. 11 is an enlarged sectional view taken along the line 11—11 of Fig. 1.

Fig. 12 is an enlarged side view of a portion of the bracket.

Fig. 13 is a plan view of the same.

Fig. 14 is an enlarged plan view of the retaining collar, and,

Fig. 15 is a perspective view of the spacing ring.

In the embodiment of the invention illustrated herewith 1 designates a window provided with the usual frame of which 2 indicates the side and 3 the top portion. A supporting bar 4 extends entirely across the window supporting a valance 5 and has its end portions inturned and secured to the top portion 3 of the window frame by screws 6 or other suitable securing means.

The main curtain supporting mechanism 100 preferably comprises duplicate structures secured to the side portions of the window frame on opposite sides thereof the mechanism on one side only of the window hav-

ing been illustrated, since the structures on opposite sides of the window are similar in all respects.

The curtain supporting mechanism located upon each side of the window comprises a vertical shaft 7 rotatably supported adjacent the top and bottom portions thereof by a bearing bracket which comprises a vertical portion 8 secured to the frame 2 of the window and which is provided with an angular base 9 having an opening 10 serving as a bearing for the shaft 7, the vertical portion 8 of the bracket being provided with an opening 11 adjacent to the top thereof by which the same may be secured to the frame 2 and an elongated opening 12 adjacent to the lower end thereof for securing the bracket to the frame. The opening 12 being elongated or arcuate permits the adjustment of the brackets to bring the curtain supporting arms on opposite sides of the window into exact alignment after the brackets are in place. A member 13, which may be made integral with the vertical portion 8 of the bracket or formed separate as shown, is provided with an opening 14 registering with the opening 11 in the vertical portion of the bracket by which the parts may be secured to the frame by a screw or other suitable fastening means. The number 13 is shaped to form a bearing 16 for the shaft 7, the bearings 10 and 16 being in vertical alignment for rotatably supporting the shaft 7. A reduced opening 18 communicates with the bearing 10 and the member 13 is shaped to provide a similar narrowed opening 19 communicating with the bearing 16.

The shaft 7 is provided with reduced portions 20 and 21 which are separated from each other by a distance equal to that separating the member 13 and base 9 of the bracket whereby the reduced portions 20 and 21 may be passed through the restricted openings 19 and 18 respectively to place the shaft 7 in the bearings 10 and 16 of the bracket structure. The shaft 7 being then raised a sufficient distance to bring the reduced portions 20 and 21 of the shaft out of registry with the restricted openings 19 and 18 the shaft will be retained against separation from the bearings until the shaft 7 is reciprocated therein to such an extent as to bring the reduced portions of the shaft into registry with the restricted openings. The diameter of the shaft 7 is such as to fit closely in the bearing openings 10 and 16, while the diameters of the reduced portions 20 and 21 of the shaft are such as to fit closely in the restricted openings 19 and 18 communicating with the bearing openings.

The angular base 9 is provided with depressions 22 arranged at right angles to each other for the purpose of locating the shaft 7 and the curtain supporting arms in the proper position relative to the window. A

locating washer 24 is provided with an opening 25 of slightly larger diameter than the opening 10 in the base 9, and has a restricted opening 26 communicating therewith of the same width as the restricted opening 18 in the base 9. The locating washer 24 is provided with depressions 27 arranged at right angles to each other which depressions are adapted to fit within the depressions 22 formed in the base 9. The edges of the locating washer 24 are preferably roughened or milled to permit the same being readily turned to bring the restricted openings 18 and 26 into or out of registry with each other as desired.

The upper portion of the shaft 7 is provided with an enlarged shoulder portion 29 which may be formed integral therewith by swaging or may be in the form of a nut threaded thereon. The enlarged portion 29 serves as a rest for the curtain supporting arms, which in the present instance are two in number although a greater number of these arms may be employed if desired. The curtain supporting arms are of similar construction, the lower arm 30 being adapted to support the curtain and the upper arm 31 the curtain draperies in the present case.

Each curtain supporting arm is formed with a loop portion 32 shaped to fit over that portion of the shaft 7 above the shoulder 29 and having a straight shank 33 from which extends a curved portion 34 fitting within a thin metal sheath 35. The metal sheath extends beyond the free end of the curved portion 34 and has its edges bent over, as shown in Figs. 6 and 7, to form sockets 36 for the reception of the ends 38 of a U-shaped extension member 39 which may be forced into the sockets formed in the metal sheath or drawn out therefrom whereby the supporting arm may be arranged of suitable length to fit windows of varying size. The U-shaped extension member 39 is provided at the end with a bend 40 to which the curtain material may be stitched in such a manner as to secure the same thereto so that the edge of the curtain will move with the extension as it is moved in or out of the sockets to fit the window.

A spacing ring 42 is positioned upon the shaft 7 above the loop portion 32 of the lower curtain supporting arm 30 and the loop portion 32 of the upper curtain supporting arm is then placed over the shaft 7 in position to rest upon the spacing ring 42. A nut 43 is then threaded upon the upper threaded end 44 of the shaft 7 and the nut is threaded down sufficiently to force the curtain supporting arms downwardly against the shoulder 29 to firmly bind the arms in position on the shaft and thus secure both of said arms against rotation on the shaft.

The shaft 7 is provided with a squared

portion 45 to assist in holding the shaft in tightening the nut 43.

A pin 50 is passed into one side of the shaft 7 and a handle 51 is secured in the shaft 7 below the pin 50 and at right angles thereto, the handle 51 extending from one side only of the shaft. Adjacent to the lower end of the shaft 7 is a curved curtain holder 53 secured on the shaft by nut 54 over which the lower portion of the curtain may be placed if desired to partially remove the same from in front of the lower part of the window.

In applying the structure to a window a screw may be passed through the openings 14 and 11 in the member 13 and bracket 8 to secure the upper portion of the bracket to the frame and a second screw passed through the slot 12 at the lower end of the bracket 7. The shaft 7 with the curtain supporting arms carried thereby may then be placed on the bracket by passing the reduced portions 20 and 21 of the shaft through the restricted openings 19 and 18 respectively. The locating washer 24 may then be placed over the base 9 with the restricted opening 26 therein in registry with the similar opening 18 in the base and the shaft raised into the position shown in Fig. 3, with the curtain supporting arms positioned below the lower edge of the valance 5. The locating washer 24 may then be turned to close the restricted opening 18 in the base and the shaft turned either 90 degrees or 180 degrees from its position as shown to turn the curtain supporting arms away from in front of the window in which position it is held by the pin 50 engaging with one of the depressions 27 in the locating washer. When it is desired to raise the curtains into operative position in front of the window the operator grasps the handle 51 and turns it to the position shown in Fig. 3, when the locating washer 24 is rotated to bring the restricted opening 26 into registry with the similar opening 18 in the base, and the shaft raised by the handle into the position shown in Fig. 1 with the handle 51 above the base 9. The locating washer 24 is then turned to cover the opening 18 in the base and the handle 51 is then permitted to rest in the depression 27 to hold the curtain in the position shown in Fig. 1 with the top of the curtain and drapery extending beneath the valance 5 to conceal the top of the curtain and drapery.

When the curtains on both sides of the window are in place they may be adjusted into exact alignment with each other by loosening the screws passed through the slots 12 and adjusting the brackets 8 around the screws passed through the openings 11.

It will be noted that the rod 4 supporting the valance is spaced outwardly from the frame 3 of the window beyond the cur-

tain supporting arms 30 and 31 when the curtain supporting arms are located in front of the window. In this way sufficient space remains between the valance supporting rod and the frame to permit the curtain supporting structure including the arms 30 and 31 being raised or lowered to bring the upper portions of the curtain and draperies beneath the valance or to permit the lowering of the curtains and draperies below the valance to remove the curtain supporting structure bodily from the brackets. The curtain supporting arms 30 and 31 are spaced from each other vertically and the upper arm 31 is off-set outwardly from the window frame beyond the lower arm 30 so that the curtains or draperies are supported and maintained separate from each other, those supported by each arm extending downwardly directly therefrom without bearing against or interfering with the disposition of the other although the spacing ring 42 may be omitted if desired so that the curtain supporting arm 31 rests upon and directly above the curtain supporting arm 30.

What I claim is:—

1. A curtain supporting structure comprising a vertically positioned rotatable shaft, a plurality of curtain supporting arms carried by said shaft, each of said arms comprising a shank portion having a loop surrounding said shaft and a curved portion extending therefrom and a substantially straight curtain supporting portion, said arms being located one above the other and off-set horizontally to permit the draperies carried by each of the arms to extend downwardly vertically therefrom without interference with the draperies carried by the other arms and a spacing member carried by said shaft intermediate the loop portions of said arms to space the arms from each other vertically.

2. A curtain supporting structure comprising bearing members provided with bearing openings and lateral openings communicating therewith, a shaft rotatably mounted in said bearing members for removal therefrom or insertion therein by lateral movement of said shaft, a plurality of curtain supporting arms carried by said shaft, said arms being spaced from each other vertically and off-set horizontally to permit the draperies carried by each of the arms to extend downwardly vertically therefrom without interference with the draperies carried by the other arms, means for rotating said shaft, and means for releasably retaining said shaft in either one of two angular positions.

3. A curtain supporting structure comprising bearing members provided with bearing openings and lateral openings communicating therewith, a shaft rotatably mounted in said bearing members for removal there-

from or insertion therein by lateral movement of said shaft, curtain supporting arms carried by said shaft and movable into position in front of the window or away from in front of the window, means for raising or lowering said shaft, and means for supporting said shaft in either its raised or lowered position.

4. A curtain supporting structure comprising a vertically positioned rotatable shaft, curtain supporting arms carried by said shaft and movable into position in front of the window or away from in front of the window, and means comprising a separate movable locating washer provided with a slot for permitting vertical movement of said shaft and having means for releasably retaining said shaft in any one of two angular positions.

20 5. A curtain supporting structure comprising a vertically positioned rotatable shaft provided with a reduced portion a curtain supporting arm carried by said shaft, a bracket provided with an opening serving as a bearing for said shaft and having a slot, formed therein communicating with said opening, the width of said communicating slot being less than the diameter of said opening and substantially equal to the diameter of the reduced portion of said shaft to permit the insertion of the reduced portion of the shaft therein, whereby said shaft may be inserted in said opening or removed therefrom by lateral movement of said shaft relative to said bracket.

6. A curtain supporting structure comprising a bracket having a pair of vertically spaced arms each of which is provided with bearing openings and having a restricted opening communicating with each bearing opening, a rotatable shaft provided with reduced portions spaced from each other a distance equal to the distance separating said spaced arms whereby said shaft may be laterally inserted in the bearing openings in said arms, and curtain supporting arms carried by said shaft.

7. A curtain supporting structure comprising a vertically positioned rotatable shaft, a plurality of curtain supporting arms carried by said shaft, each of said arms comprising a shank portion having a loop surrounding said shaft and a curved portion extending therefrom, a metal sheath surrounding the curved portion and extending therefrom and provided with sockets and an extension member having ends adjustably positioned in the sockets, and means for securing the said arms to said shaft to prevent movement of said arms independently of said shaft.

8. In a curtain supporting structure, a vertically positioned rotatable shaft, brackets provided with openings serving as bearings for said shaft one of said brackets being pro-

vided with a lateral opening communicating with said bearing opening of less width than the diameter of said bearing opening, said shaft being provided with a reduced portion adapted to fit the lateral opening in said bracket whereby the said shaft may be moved laterally within the bearing opening in said bracket.

9. In a curtain supporting structure, a vertically positioned rotatable shaft, a curtain supporting arm carried by said shaft, said curtain supporting arm comprising a shank provided with a portion fitting about said shaft and a curved portion, a strip of bendable metal secured to the curved portion and extending therefrom, said strip being shaped to provide sockets adjacent to one end thereof and an extension member provided with ends fitting within said sockets whereby the said extension member may be adjusted to vary the length of said curtain support.

10. In a curtain supporting structure a bracket having a pair of outwardly extending arms each of which is provided with a bearing opening and a restricted opening communicating therewith, means for securing the upper end of said bracket structure to a window frame, means for adjustably securing the lower portion of said bracket to the frame, and a vertical shaft provided with reduced portions adapted to enter the restricted openings in said bracket arms whereby the shaft may be positioned in the bearing openings.

11. In a curtain supporting structure, a vertically adjustable rotatable shaft, curtain supporting arms carried by said shaft, a bracket having arms provided with bearing openings for rotatably supporting the shaft, a locating washer carried by one of said arms and provided with radial depressions, and pins carried by said shaft engageable with the depressions of said washer to retain the shaft in one or another of several angular positions.

12. In a curtain supporting structure, a vertically adjustable rotatable shaft, curtain supporting arms carried by said shaft, a bracket having arms provided with bearing openings for rotatably supporting the shaft, and means in different vertical positions on said shaft and engageable with one of said bracket arms to support said shaft in different vertical and angular positions.

13. In a curtain supporting structure, a vertically adjustable rotatable shaft, curtain supporting arms carried by said shaft, a bracket having arms provided with bearing openings for rotatably supporting the shaft, and means in different vertical positions on said shaft and engageable with one of said bracket arms to support said shaft in different vertical and angular positions and a locating member adapted to be supported by said bracket arm and provided with de-

pressions for the reception of said last named means to retain said shaft in one or another of several angular positions.

14. A curtain supporting structure comprising vertically aligned bracket members provided with bearing openings and reduced lateral openings communicating therewith, a vertically positioned shaft provided with reduced portions fitting the reduced lateral

openings of the brackets and bodily insertible within or removable from said bracket members by lateral movement of said shaft, and curtain supporting arms carried by said shaft.

In testimony whereof I have affixed my signature.

GEORGE W. DOVER.
